UNITED STATES PATENT OFFICE.

JOHN D. LAWRENCE AND STANLEY W. NICHOLSON, OF TOLEDO, OHIO, ASSIGNEES TO THE DURA COMPANY, OF TOLEDO, OHIO, A CORPORATION OF DELAWARE.

METHOD OF FORMING SHEET-METAL HANDLES.

Application filed October 11, 1920. Serial No. 416,246.

To all whom it may concern:

Be it known that we, JOHN D. LAWRENCE and STANLEY W. NICHOLSON, both citizens of the United States of America, residing at Toledo, in the county of Lucas and State of Ohio, have invented certain new and useful Improvements in Methods of Forming Sheet-Metal Handles, of which the following is a specification, reference being had 10 therein to the accompanying drawings.

This invention relates to a method of forming sheet metal handles and has an especial application to the forming of a handle for actuating window control mechanism on a motor vehicle.

In the drawings:

Figure 1 is a plan view of the blank from which the handle is to be formed;

Figure 2 is a view of the same subsequent 20 to the first stamping operation showing the cups or depressions formed by said first operation;

Figure 3 is a side view of the blank as shown in Figure 2;

Figure 4 is a side view showing the form assumed by the blank subsequent to the second stamping operation;

Figures 5, 6 and 7 are cross sections respectively taken on lines 5-5, 6-6 and 30 7-7 of Figure 4;

Figure 8 is a side view of the completed handle.

It will be observed that the initial blank consists of the flat sheet metal stamping A 35 having an enlarged circular portion B at one extremity and having at its other extremity a somewhat smaller enlarged portion C which is of a conventional heart shape except that it lacks the pointed portion. The enlargement C is recessed as indicated at D along the central line of the blank. The first stamping operation produces a cup-shaped recess E centrally in the circular enlargement B, said recess having a tapering wall E'. Also there are produced by said first stamping operation two shallow depressions F in the enlargement C 45 symmetrically located at each side of the center line of the blank.

The second stamping operation transforms the center portion or stem of the blank to a U-shape and places the opening of the U-shaped stem in communication with the cup-shaped recess E. Also the two

symmetrical portions of the enlargement C 55 at each side of the center line of the blank are bent into an opposed abutting relation by said second stamping operation.

The final operation subjects the stem of the handle to a slight curvature as is indicated in Figure 8 and bends the enlarged end portion C at an angle of substantially 45° to said stem.

A handle thus formed possesses a high degree of strength, a pleasing appearance 65 and may be produced in quantities at a comparatively low expense.

What we claim as our invention is:

1. The method of forming a handle consisting in first forming a sheet metal blank 70 having enlarged end portions, one of which is circular, producing by an initial stamping operation a cup-shaped recess in said circular end portion and a pair of symmetrical recesses at each side of the center line of the blank in the other enlarged end portion thereof, imparting a U-shape to the center portion of the blank by a second stamping operation and by the same operation bending the symmetrically recessed 75 portions into opposed relation.

2. The method of forming a handle comprising forming a sheet metal blank having enlarged end portions one of which is circular, producing a cup-shaped depression 80 centrally in said circular end portion by an initial stamping operation and by the same operation producing symmetrical depressions in the other end portion one at each side of the center line of the blank, imparting a U-shape to the center portion of the blank by a second stamping operation and by the same operation bending said symmetrically recessed portions at one end into opposed relation and imparting a gradual 85 curvature to the center portion of the blank by a third operation and by the same operation bending the opposed end portions thereof at an acute angle to the center portion.

3. The method of forming a stamped sheet metal handle comprising the forming of the blank having an enlarged circular portion at one end and an enlarged portion at its other end at an approximate heart-shape, said last-mentioned end having a recess along the center line of the blank, forming a cup-shaped recess centrally in said 100 105

center portion by an initial stamping operation and forming symmetrical depressions by the same operation in the heart-shaped end portion of each side of the center line, and by subsequent operation imparting a U-shape to the center portion of the blank and folding said heart-shaped portion substantially upon the center line to establish an opposed relation between the symmetrical recess thereof.

4. The method of forming a stamped sheet metal handle consisting in first forming a sheet metal blank having enlarged end portions producing by an initial stamping operation a recess in one of said end portions and symmetrically arranged recess in the other of said end portions and imparting by a second stamping operation a U-

shape to the center portion and to said last-mentioned end portion of the blank.

5. The method of forming a handle comprising forming a sheet metal blank having enlarged end portions, stamping a recess in one of said end portions and a pair of symmetrically arranged recesses in the other of said end portions and on opposite sides of the center line of said blank, channeling said blank by folding a portion of said blank along its center line and bringing said symmetrically arranged recesses into opposed relation.

In testimony whereof we affix our signatures.

JOHN D. LAWRENCE.
S. W. NICHOLSON.
